UNITED STATES PATENT OFFICE.

CHARLES H. JAMES, OF SPOKANE, WASHINGTON.

MANIFOLDING DEVICE.

1,189,955.

Specification of Letters Patent.

Patented July 4, 1916.

Application filed March 29, 1916. Serial No. 87,556.

To all whom it may concern:

Be it known that I, CHARLES H. JAMES, a citizen of the United States, residing in Spokane, in the county of Spokane and State of Washington, have invented certain new and useful Improvements in Manifolding Devices, of which the following is a specification.

This invention relates to writing pads of the class in which provision is made, by means of carbon or other transfer or manifolding paper, for obtaining one or more extra copies of the written matter whether it be ordinary correspondence, sales entries, orders, business forms, bills of lading or otherwise, and my invention consists in providing a holder for a flat pad of superimposed sheets of writing paper which is equipped with a clamp for holding the paper firmly in place, a cylindrical holder of novel construction for holding a roll of manifolding paper and a table carried by the roll-holder which is adapted to be inserted in the pad immediately below the sheets of paper being written upon and which serves as a firm foundation therefor to facilitate in obtaining good impressions on all the sheets which it supports.

My improvements are illustrated in the accompanying drawings, in which—

Figure 1 is a perspective view of a manifolding device embodying my improvements. Fig. 2 shows a longitudinal vertical section thereof. Fig. 3 is a detail view in perspective of the roll-holder and the table connected therewith. Fig. 4 is a perspective view of one of the heads or caps of the roll-holder.

The pad of paper X is supported by a base piece A made of any suitable material, such as wood, and carrying at one end a spring clip B which engages the pad and holds it in place on the base. This clip may be of any suitable construction, but it is preferably made as shown, comprising a sheet metal pad-engaging member b having a pad-engaging edge b' and formed with lugs b² pivotally mounted on a rod c held against turning in brackets C attached to the base A as shown. A spring D encircling the rod and attached thereto at one end has an end portion d bearing against the member b and normally pressing its edge b' against the pad. The brackets C are preferably made of sheet metal, extend beyond the end of the base piece, and have enough

resiliency to permit them to be spread apart sufficiently to allow the rod to be disconnected from them if it be necessary to remove the clip for any purpose, as for adjusting or renewing the spring.

Preferably the pad is made of loose sheets of paper, i. e., paper not pasted or otherwise connected and in order that the sheets may be held evenly I provide corner gages E which are rectangular in cross section and preferably formed integrally with the brackets C. By this simple construction the sheets are held firmly and evenly in place, but one or more sheets may be quickly removed by suitably operating the clip.

The base piece may be of any suitable size. In practice it is made in standard sizes corresponding to the sizes in which paper is usually cut and the corner gages E are so located as to hold paper of standard size.

At the opposite end of the base piece is mounted a cylindrical casing F for a roll of carbon or other manifolding paper Y. This casing is preferably made of sheet metal and is formed with a slot f which extends longitudinally from end to end of the cylinder, the metal on the upper edge of the slot being beaded as indicated at f' and the metal below the slot being flanged as shown at f². Each end of the cylinder is closed by a removable cap F', the rim of which is notched as indicated at f³ to receive the bead f' and the flange f². Each cap is provided with a trunnion g which extends into an elongated opening or vertical slot h in a bracket H attached to the base piece A. Each of these brackets is preferably made of sheet metal and projects beyond the end of the base piece, said brackets having enough resiliency to permit them to be spread apart to allow the casing to be removed when desired.

To the flange f² of the casing is secured a table T which is rectangular in outline and of approximately the dimensions of the pad. It is so connected with the case F that it moves simultaneously therewith when the latter is adjusted. This table is preferably made of sheet metal and the best results are obtained when thin sheet metal is employed which is somewhat flexible but which is yet thick enough to provide an unyielding support for the paper.

The carbon or other manifolding paper may be withdrawn to the desired extent

from the casing through the slot f and placed between sheets of paper, being unwound from the roll for this purpose. Any desired number of sheets of manifolding 5 paper may be wound together so as to supply, if desired, a plurality of sheets for making a plurality of copies at one writing.

When the pad is thick good impressions cannot be obtained without using the table 10 and this, it will be observed, is so connected with the roll-casing that it is held in line with the pad immediately below the sheets in use and it affords a firm foundation therefor.

15 When commencing to use the device the desired number of sheets are raised from the pad while being still held at one end by the clip and the table is first laid on the top sheet of the pad, then a sheet of writing 20 paper is laid and spread on the table and next a sheet of manifolding paper is in like manner laid on the writing paper carried by the table, then another sheet of writing paper is laid on the carbon or manifolding 25 sheet, then if desired another sheet of carbon paper is laid, and so on, the last sheet laid of course being writing paper. Obviously the number of carbon sheets or the 30 number of sheets of writing paper employed may be varied, but provision is made for making any desired or reasonable number of copies at one writing. After the writing is completed the casing F is turned in its bearings so as to partially withdraw 35 the flexible table T and the sheets of carbon from the pad or away from the clip end of the pad, and in so doing the sheets will be raised to some extent so that the thumb or fingers of the user can be inserted beneath 40 the table and when this is done the sheets above the table can be easily separated from the manifolding sheets and then by suitably manipulating the clip B they may be detached from the device.

45 It will be observed that the table is so connected with the roll-casing that it may be lowered or raised to correspond with the thickness of the pad and may always be held in a plane substantially parallel with the 50 plane of the top sheets of writing paper composing the pad. The carbon or manifolding sheets are in like manner delivered in a plane substantially coincident with the plane of the sheets being written upon.

55 In order to hold the bead f' and the flange f^2 a proper distance apart and to prevent them from spreading I employ a clip M which also serves as a handle for the roll-casing. This clip has jaws m which grip 60 the casing and a bent or looped portion m' which gives resiliency to the clip and also serves as a hand-piece.

When the roll of manifolding paper has run out or is completely used up, the casing 65 F may be removed by simply spreading

apart the brackets H , removing the casing and taking off one of the end caps F' .

While I prefer to use a roll of manifolding paper, the device is also adapted to hold separate sheets of manifolding paper cut to the proper size. Such sheets may be clamped between the bead f' and the flange f^2 , the caps F' serving to hold the bead and the flange tightly and the clip M also serving this purpose. While I prefer to use 70 loose sheets in the pad, inasmuch as they can be very easily withdrawn when written upon, yet, of course, a pad composed of connected sheets or sheets connected and perforated may obviously be used if desired. 75

The device as a whole is simple in construction, can be manufactured at small cost and yet can be easily operated by any one with the advantageous results hereinbefore specified. 80

85 When the parts of the device are assembled, as shown in Fig. 1, the resilient brackets bear upon the capped ends of the cylindrical casing with sufficient pressure to hold said casing in the position to which it 90 is set, whether it be in the position shown in Fig. 2, or whether it be moved to a plane above or below the position there shown. This is an important feature of the device as it holds the table and the manifolding 95 sheets in a true horizontal plane beneath the sheets being written upon and without danger of their being moved from this position until the device is designedly actuated to move them. 100

I claim as my invention:

1. A manifolding device, comprising a base piece, a pad clip mounted at one end thereof and a roll holder at the opposite end of the base piece having trunnions mounted 105 in slotted bearings and movable in a plane at right angles to that of the pad.

2. A manifolding device, comprising a base piece, a pad-clip mounted at one end thereof and provided with corner gages for 110 the pad, and a roll-holder for manifolding material mounted at the opposite end of the base piece.

3. A device of the character described embodying a base, means at one end of the base 115 for holding one edge of a paper pad and a writing surface pivotally mounted to move about an axis at the other end of the base to normally lie in the plane of the paper pad and to be swung about said axis away from 120 the pad.

4. A device of the character described embodying a base, means at one end of the base for holding one edge of a paper pad and a table pivotally mounted to move about 125 an axis at the other end of the base to normally lie in the plane of the paper pad and to be swung about said axis away from the pad.

5. A manifolding device, comprising a 130

- base piece, a paper clip connected therewith, a roll casing for manifolding material, brackets having arms attached to edges of the base piece and having also resilient portions extending beyond the end of the base piece formed with upwardly projecting roll-supporting members and which are detachably connected with said roll-casing.
6. A manifolding device, comprising a base piece, a paper clip connected therewith, a roll-casing for manifolding material, resilient brackets projecting from one end of the base piece having slots disposed in a plane transverse to that of the base piece and trunnions on the roll-casing adapted to move in said slots.
7. A manifolding device, comprising a base piece, a pivotally mounted casing for manifolding material, and a table carried by said casing.
8. A manifolding device, comprising a base piece, a roll-casing at one end of the base piece, bearings in which the casing is adapted to turn, and a table of flexible sheet material carried by the roll.
9. A manifolding device, comprising a base piece, a roll-casing provided with a longitudinal slot through which manifolding material is delivered, and a flexible sheet metal table attached to the casing below said slot.
10. A device of the character described embodying a base, means at one end of the base for holding one edge of a paper pad, and a writing surface pivoted to move about a horizontal axis across the opposite end of the base and to swing upwardly and outwardly from the paper pad.
11. A manifolding device, comprising a base piece, a pivotally mounted cylindrical casing for manifolding material which is formed with a longitudinal slot for the delivery of the material and a clip applied to the casing for preventing the slot from opening prematurely and which also serves as a handle for turning the casing.
12. A manifolding device, comprising a base piece, a cylindrical casing for a roll of manifolding material which is formed with a slot extending from end to end thereof, removable caps at opposite ends of the casing provided with laterally extending trunnions, brackets of resilient material attached to and extending from the base piece and which are provided with slots into which the trunnions of the casing extend and in which they are free to turn, and a table of flexible material attached to the casing below the delivery slot thereof.
13. A manifolding device, comprising a base piece, a pivotally mounted casing for manifolding material, and a writing surface or table pivotally mounted to normally lie in the plane of the paper pad and to be swung on its pivot away from the pad.
14. A manifolding device, comprising a base piece, means at one end of the base for holding one edge of a paper pad, a casing for manifolding material and a table pivotally mounted adjacent said casing to normally lie in the plane of the paper pad and to be swung on its pivot away from the pad.
- In testimony whereof, I have hereunto subscribed my name.

CHARLES H. JAMES.
